HENRY W. HARPER, OF BERLINSVILLE, PENNSYLVANIA.

Letters Patent No. 95,341, dated September 28, 1869; antedated March 29, 1869.

IMPROVED MACHINE FOR GRINDING AND POLISHING SCHOOL-SLATES.

The Schedule referred to in these Letters Patent and making part of the same.

To all whom it may concern:

Be it known that I, HENRY W. HARPER, of Berlinsville, Northampton county, Pennsylvania, have invented an Improved Machine for Grinding and Polishing School-Slates; and I do hereby declare the following to be a full, clear, and exact description of the same, reference being had to the accompanying drawing, and to the letters of reference marked thereon.

My invention consists of certain mechanism, fully described hereafter, for grinding and polishing crude slates, and rendering them available as school-slates.

In order to enable others skilled in the art to make and use my invention, I will now proceed to describe its construction and operation, reference being had to the accompanying drawing, which forms a part of this specification, and in which—

Figure 1 is a vertical section, on the line 1-2, fig. 3, of my improved slate-grinding and polishing machine;

Figure 2 is a vertical section on the line 3-4, fig. 3;

Figure 3 is a plan view, partly in section; and

Figures 4 and 5, detached views, illustrating my invention.

Similar letters refer to similar parts throughout the several views.

A is the frame of the machine, in suitable bearings on which, turn the vertical shafts B, C, D, E, and F, and the horizontal shaft G, each shaft being provided with a suitable driving-pulley.

A horizontal driving-disk, H, secured to the vertical shaft B, rests upon a collar, a, and is contained within an annular metallic band, b, which is secured to the four cross-pieces c of the frame A.

Four rods, d, (see fig. 4,) passing through openings in the band b, meet at a central hub, e, through which the shaft B passes freely.

Above the disk H, and upon the shaft B, is a sleeve, I, to the lower end of which is secured a grinding-disk, J, which turns partly within the band b, above described, and which has four or more slits, f.

This disk may be raised or lowered, at pleasure, by means of a weighted lever, g, which is hung to the frame A, and whose forked short arm enters an annular groove, h, formed in the sleeve I.

The shaft B is furnished with a band-pulley, j, and the sleeve I with a pulley, k, so that the two grinding-disks H and J may be revolved in opposite directions.

The vertical shaft C, as well as the shaft E, may be raised or lowered by a weighted lever, m, or other suitable appliances.

On the upper end of the shaft C is a horizontal wheel, on the edge of which is a band, n, projecting above the face of the wheel, as shown in fig. 2.

A split ring, p, which rests in the circular recess q of the wheel, also projects above the face of the same,

and is connected to the band n by bolts r, which pass through the wheel.

By turning the nuts s upon the ends of these bolts r, the diameter of the split ring p may be increased or diminished at pleasure.

Upon the upper end of the shaft D, and overlapping the wheel K, is a grinding-disk, L.

To the upper end of the shaft E is secured a wheel, M, precisely similar to the wheel K before described, this wheel M being overlapped by the grinding-disk L, on the shaft D, as well as by a similar disk, P, on the shaft F.

Upon the horizontal shaft G is secured a polishing-wheel, R, and to a sleeve, S, turning upon the said shaft, is secured a similar polishing-wheel, T.

Passing between these wheels, and above the shaft G, is a rod, U, secured to standards v, and tightened by a nut, w. (See figs. 1 and 3.)

By means of a lever shown in red lines, fig. 3, the wheel T is kept close up to the rod U.

The rough slab to be converted into school-slates is split or sawed to a proper thickness, and then cut to the size desired. These rough slates, which are similar to those used for roofing, are placed upon the grinding-disk H, between the bars d, as shown in fig. 4, the disk J being first raised by means of the lever g. Upon releasing the lever, the disk J is lowered until it rests upon the slates, when the two disks are caused to revolve in opposite directions, as shown by the arrows, fig. 3. The slates are prevented from being carried round with either of the stones by the bars d, and the grinding is facilitated by the use of sand, which is introduced to the slates through the slits f of the upper disk, and the pressure upon the slates is regulated by the weight upon the long arm of the lever g.

Between the disks H and J, the slates are reduced to a uniform thickness, and all prominent inequalities removed. Thence they are removed to the wheel K, and placed radially between the rings n and p, as shown in fig. 3. When the required number of slates has been placed on the wheel, the nuts s are tightened, thereby increasing the diameter of the split ring p, and forcing the slates against the band n, between which and the ring they are securely confined.

The shafts C and D are now rapidly rotated in opposite directions, and the wheel K is elevated toward the grinding-disk L, until the slates are in contact with and are acted on by the said grinding-wheel. When properly reduced, the slates are turned, so that their opposite faces may be acted on.

From the wheel K, the slates are removed to the wheel M, and confined to the same, so as to be acted on by what may be termed the first polishing-wheel P, the full weight of which on the slates is not necessary;

hence the shaft F of this polishing-wheel rests on the spring t.

The slates are taken from the wheel M, and submitted to the final or polishing-process, which is as follows:

A high rate of speed is imparted to the polishing-wheels R and T, which turn in opposite directions, as shown in fig. 3, and the slates to be polished are placed, edge downward, on the rod U, and passed between the wheels, dry slate-powder, or an equivalent substance, being used in the operation. The wheel T is pushed up to the slates by its lever shown in red lines, fig. 3.

It will be observed, that the wheel K always revolves in the same plane, that the grinding-disk L can be raised and lowered, whereas the polishing-disk P revolves in the same plane, while the wheel M admits of being raised or lowered—an arrangement which prevents the grinding-disk L from coming in contact with the slates confined on the wheel M for being acted on by the polishing-disk P.

In many cases, the slates are of so perfect a character, that the preliminary grinding by the disks J and H may be dispensed with, the slates being at once placed on the wheel K, to be acted on by the grinding-disk L. The final polishing-process, by the wheels R and T, may also be dispensed with, if the polishing-disk P be sufficiently fine.

Both the grinding-disk L and polishing-disk P have surfaces of emery, or consist of the well-known emery-wheels now in general use for grinding and polishing; in fact, I have found emery to be a material especially applicable to the reduction and polishing of slates.

If desirable, a second grinding-disk, L', shown by dotted lines, figs. 2 and 3, may be used to act on the slates in the wheel K.

I do not desire to confine myself to any particular arrangement of frame-work, or to the precise construction or arrangement of the several parts herein described; but

I claim as my invention, and desire to secure by Letters Patent—

1. The two horizontal grinding-disks J and H, revolving in contrary directions, in combination with the bars d, or their equivalents.

2. The disk H, and its band, d, in combination with the movable disk J, and its slots, f.

3. The revolving wheel K or M, constructed substantially as described, for holding the slates, in combination with a grinding or polishing-wheel or disk.

4. The wheel K, its band, the split ring p, and bolt r.

5. The combination of a revolving wheel, K or M, for holding the slates, with one or more horizontal revolving polishing or grinding-disks, arranged to overlap the said wheel, as set forth.

6. The combination of the two vertical polishing-wheels T and R with the bar V, for the purpose specified.

In testimony whereof, I have signed my name to this specification, in the presence of two subscribing witnesses.

H. WM. HARPER.
